UNITED STATES PATENT OFFICE.

CHARLES CRIST DELMONICO, OF MORRISTOWN, NEW JERSEY.

DESIGN FOR A BUTTON, BADGE, OR EMBLEM.

52,070.

Specification for Design.

Patented June 4, 1918.

Application filed January 29, 1918. Serial No. 214,432. Term of patent 7 years.

To all whom it may concern:

Be it known that I, CHARLES CRIST DELMONICO, a citizen of the United States, residing at Morristown, in the county of Morris and State of New Jersey, have invented a new, original, and ornamental Design for a Button, Badge, or Emblem, of which the following is a specification, reference being had to the accompanying drawing, forming part thereof.

The figure of the drawing shows the design in plan on a circular ground and in a form suitable for application to a button, badge or other emblem.

I claim:

The ornamental design for a button, badge or emblem as shown.

CHARLES CRIST DELMONICO.
